SOLENOID VALVE UNIT

Ernest J. Svenson, 2330 23rd Ave., Rockford, Ill. 61101

Filed Aug. 2, 1968, Ser. No. 13,018

Term of patent 14 years

Int. Cl. D23—01

U.S. Cl. D23—19

Fig. 1.

Fig. 2.

Fig. 3.

FIG. 1 is a top plan view of a solenoid valve unit showing my new design;

FIG. 2 is a side elevational view thereof; and

FIG. 3 is a left end elevational view thereof.

The dominant features of my design reside in the portions shown in full lines.

I claim:

The ornamental design for a solenoid valve unit, as shown and described.
